(57) **CLAIM**

The ornamental design for a cup holder tray, as shown and described.

DESCRIPTION

FIG. 1 is a top, right, and front perspective view of a cup holder tray, showing my new design;

FIG. 2 is a top, right, and front perspective view thereof, shown with the cup holder detached;

FIG. 3 is a top plan view thereof, shown with the cup holder detached;

FIG. 4 is a top, right, and front perspective view thereof, shown with the tray detached;

FIG. 5 is a bottom right perspective view thereof, shown with the tray detached;

FIG. 6 is a top, right, and front perspective view thereof, shown in a folded status;

FIG. 7 is a bottom perspective view thereof, shown in a folded status;

FIG. 8 is a bottom plan view thereof, shown in a folded status; and,

FIG. 9 is a right side elevational view thereof, shown in a folded status.

The broken lines in the figures illustrate the portions of the cup holder tray that form no part of the claimed design.
